UNITED STATES PATENT OFFICE.

WILLIAM M. BARBER, OF PHENIX, RHODE ISLAND, ASSIGNOR TO DRAPER COMPANY,
OF HOPEDALE, MASSACHUSETTS, A CORPORATION OF MAINE.

PICKER-CHECK FOR LOOMS.

981,050.

Specification of Letters Patent. Patented Jan. 10, 1911.

Application filed September 20, 1910. Serial No. 582,837.

To all whom it may concern:

Be it known that I, WILLIAM M. BARBER, a citizen of the United States, and resident of Phenix, county of Kent, State of Rhode Island, have invented an Improvement in Picker-Checks for Looms, of which the following description, in connection with the accompanying drawing, is a specification, like characters on the drawing representing like parts.

This invention has for its object the production of simple and efficient means to check the movement of the picker in a loom, the checking means being so constructed and arranged that it coöperates with the picker-stick as it approaches each end of its stroke and by frictional engagement stops it at the proper point without undue wear or shock.

The checking means is located beneath the lay and as it in no way interferes with the ejection of a spent bobbin in automatic filling-replenishing looms of the Northrop type it is well adapted for use in connection therewith, but my invention is not by any means restricted to such use.

Herein I have illustrated one practical embodiment of my invention in connection with the lay of a Northrop loom at the replenishing side thereof, such a loom, for instance, as is shown in United States Patent No. 529,940 granted to Northrop November 27, 1894.

The checking action upon the picker-stick can be readily adjusted to any desired degree, as will appear hereinafter.

The novel features of my invention will be fully described in the subjoined specification and particularly pointed out in the following claims.

Figure 1 is a front elevation of the lay of an automatic filling-replenishing loom at the replenishing side thereof, with one embodiment of my invention applied thereto; Fig. 2 is a top plan view of the checking means detached from the loom, the picker-stick being shown in section; Fig. 3 is a transverse section on the line 3—3, Fig. 1, looking toward the left.

The longitudinally-slotted lay 1 and its race-plate 2, the front and back plates 3, 4 of the shuttle-box, the cover-plate 5, and binder 6, Fig. 1, may be and are all of usual or well known construction, the picker-stick 7 traversing the slot in the lay behind the

front guide 8 which latter is bolted at 9 to the lay, the deflecting plate or guide 10 for the spent bobbin being located at the inner end of the front guide 8, as usual. Said front guide is provided with a front- 60 wardly extended, slotted ear 11 which herein forms one of the supports for the picker check, the other support being shown in Fig. 3 as a bracket 12 bolted to the back of the lay behind said ear 11. Upon each of 65 said supports I bolt a plate 13, which in practice is substantially horizontal and extended outward toward the loom side, the inner end of each plate having formed upon or secured to it a downturned tubular boss 70 14, through which extends a headed fulcrum stud 15. The fulcra 15 are parallel and opposite to each other, and extend through apertured lateral ears 16 in the checking members, shown clearly in plan 75 view, Fig. 2, each member presenting oppositely extended inner and outer arms 17, 18, the latter being somewhat longer, and the flat and smooth inner faces of each pair of the arms are at an obtuse angle to each 80 other. When the two members are in operative position in front and behind the path of the picker-stick the arms 17 converge, as do also the arms 18 at the outer side of the fulcra 15. 85

The checking members are conveniently made of metal, and are substantially rigid inherently, but they can swing laterally about their fulcra and when so swung their outer ends will approach when their inner 90 ends are separated, and vice versa, such separation being effected by the intervening picker-stick 7, as shown in Fig. 2.

Referring to Figs. 1 and 3 the ears 16 of the checking members abut against the 95 lower ends of the bosses 14, and a spring 19 is interposed between each ear and check-nuts 20 screwed onto the lower end of the fulcrum stud, to maintain the ear 16 of a checking member in frictional engagement 100 with the adjacent boss 14. The more the spring is compressed by setting up the corresponding check-nuts the harder will the ear be pressed against the boss, and consequently the greater will be the frictional 105 resistance offered to any lateral swinging movement of a checking member about its fulcrum stud. I prefer to interpose washers 21, 22 between the ends of the spring and the adjacent parts, to wit, the ear 16 110

and the check-nuts. The checking members are spaced apart to properly coöperate with the picker-stick as it nears each end of its stroke, and to be pressed apart as the stick 5 completes its stroke, the resistance to the lateral swing of the checking members, governed by the friction means described, determining the amount of check exerted upon the picker-stick. Such resistance can 10 be readily increased or diminished, according to the requirements of the particular loom to which the checking means is applied. Supposing the picker-stick separates the arms 18 on its outward stroke then the 15 arms 17 will be moved toward each other, as in Fig. 2, and when the stick moves inward it will impinge upon and separate the said arms 17, and in so doing will be checked, but at the same time the outer arms 20 18 are moved toward each other and reset for coöperation with and checking of the picker-stick on its next outward stroke. Thus the checking members are double-acting 25 and the picker-stick on either stroke sets the checking members to coöperate properly therewith on its next stroke. The outer arms 18 are made somewhat longer than the inner arms 17 in order to properly locate the impinging portions of both sets 30 of arms with relation to the picker-stick as it swings inward and outward. Inasmuch as there is little wear between smooth metal faces and wood there is insignificant wear upon the picker-stick due to the coöperation 35 therewith of the checking members, and as the friction devices are always acting upon such members the latter remain in any given angular position relative to their fulcra until positively moved therefrom by impact 40 of the picker-stick thereon.

Various changes or modifications in details of construction and arrangement may be made by those skilled in the art without departing from the spirit and scope of my 45 invention as set forth in the claims annexed hereto.

Having fully described my invention, what I claim as new and desire to secure by Letters Patent is:

50 1. In a loom, in combination, a lay longitudinally slotted for the picker-stick, said picker-stick, and checking means therefor comprising oppositely positioned checking members fulcrumed between their ends and 55 converging toward their outer and inner ends, to frictionally engage the picker-stick on its outward and inward strokes, respectively, the picker-stick traveling between said members, fulcra for the latter fixedly connected with the lay and upon which the 60 members swing laterally when impinged upon by the picker-stick, and means to resist such lateral movement of the checking members and thereby bring the picker-stick to 65 rest at each end of its travel.

2. In a loom, in combination, a lay longitudinally slotted for the picker-stick, said picker-stick, and checking means therefor comprising elongated members fulcrumed between their extremities at the front and rear of the path of the picker-stick and converging toward their inner and outer ends, engagement with the picker-stick on either stroke acting to separate laterally the adjacent ends of the checking members and 70 cause their other ends to approach each other, fulcra for said members, fixedly connected with the lay and upon which the members swing laterally, and yielding means to resist such lateral movement and thereby cause 75 said members to check the movement of the picker-stick at each end of its travel.

3. The combination with the lay of a loom, and a picker-stick, of checking means comprising opposed checking members to coöperate with and check the picker-stick at each end of its stroke, fulcra carried by the lay and upon which said members are mounted between their inner and outer ends to swing laterally, and friction devices acting upon the checking members adjacent their fulcra to resist lateral movement thereof due to engagement with the picker-stick at either the inner or the outer ends of said members. 85 90 95

4. The combination with the lay of a loom, and a picker-stick, of checking means comprising inherently rigid checking members pivotally mounted at the front and rear of the picker-stick path, the opposite faces of 10 said members converging from their fulcra to their extremities, fulcra fixedly connected with the lay and upon which said checking members are adapted to swing laterally, the engagement of the picker-stick by said members near one end setting the opposite end thereof to coöperate with and check the picker-stick on its next stroke, and adjustable friction controlling means to regulate the resistance of said members to swinging 11 movement when engaged by the picker-stick.

5. The combination with the lay of a loom, and a picker-stick, of checking means comprising opposed checking members to coöperate with and check the picker-stick at 11 each end of its stroke, fulcra carried by the lay and upon which said members are mounted to swing laterally, and friction devices acting upon the checking members to resist lateral movement thereof due to engagement with the picker-stick, each device comprising a fixed contact surface and a co-operating surface on the checking member, a spring to yieldingly press said surfaces together, and means to vary the action of the 12 spring thereupon.

6. The combination with the lay of a loom, and a picker-stick, of checking members mounted opposite each other at the front and rear, respectively, of the path of the picker- 13

stick, a fulcrum fixedly connected with the lay and upon which one of said members is mounted substantially midway between its ends and adapted to swing laterally, the opposed impact faces of said members converging toward their extremities adjacent the inner and outer ends of the stroke of the picker-stick, whereby the engagement of the picker-stick with said members near either 10 the inner or the outer extremity thereof swings the fulcrumed member and causes the opposite extremities of said members to

approach each other, and a spring-controlled friction device acting to resist lateral swinging movement of said fulcrumed member in either direction. 15

In testimony whereof, I have signed my name to this specification, in the presence of two subscribing witnesses.

WILLIAM M. BARBER.
